UNITED STATES PATENT OFFICE.

WILLIAM S. FOX, OF PHILADELPHIA, PENNSYLVANIA.

DESIGN FOR A BOTTLE.

SPECIFICATION forming part of Design No. 28,969, dated July 5, 1898.

Application filed June 2, 1898. Serial No. 682,401. Term of patent 3½ years.

To all whom it may concern:

Be it known that I, WILLIAM S. FOX, a citizen of the United States, and a resident of the city of Philadelphia, State of Pennsylvania, 5 have invented and produced a new and useful Design for Glass Bottles, of which the following is a specification.

In the accompanying drawings, Figure 1 is a perspective view of my design of glass bottle, and Fig. 2 is a cross-sectional view of the same on the line *xx* of Fig. 1.

The leading feature of my invention consists in a four-sided glass bottle having the plane of one side substantially convex and the remaining three sides in their outer surfaces having longitudinal subdivisions, each subdivision being slightly curved or rounded, as best illustrated in cross-section, as in Fig. 2, the greatest thickness of each curved portion being at the center and curving off to the deepest part of the adjacent grooves, forming the subdivisions. Each side of the bottle is of the greatest thickness at about the center, as at the line *xx*, Fig. 1, curving off gradually toward the neck and base. The base 25 is rectangular, with vertical sides of slight depth, toward which the curved lines of the sides converge. The top of the cylindrical neck at the mouth is flat, horizontally considered, with an overhanging lip. At the base 30 of the neck is a slight cylindrical enlarge-

ment, and beneath this a convexed surface upwardly facing around the neck, having rectangular vertical sides of slight depth toward which the curved upper portions of the sides 35 converge.

In the drawings, *A* represents the vertically-disposed subdivisions of the subdivided sides formed by the channels *a* and having curved or rounded faces in cross-section, thus forming in the said three sides a substantially fluted surface. The plain convexed side is represented by *b* in section in Fig. 2. All the sides at their lower portion converge toward the upper portion of the vertical edges of the 45 base *c*, and the upper portions of the sides of the bottle in like manner converge toward the side walls of the upper convexed portion *d*, from which the neck *e* protrudes, having the rounded portion *f* at its base and the flattened overhanging lip *g* at the top.

Having thus described my invention, what I claim, and desire to secure by Letters Patent, is—

The design for a bottle substantially as 55 shown and described.

In witness whereof I have hereunto set my hand this 1st day of June, A. D. 1898.

WILLIAM S. FOX.
